W. G. GREY

DUPLEX UMBRELLA

Filed Feb. 24, 1925

UNITED STATES PATENT OFFICE.

WILLIAM GEORGE GREY, OF BALTIMORE, MARYLAND.

DUPLEX UMBRELLA.

Application filed February 24, 1925. Serial No. 11,286.

This invention relates to duplex umbrellas and has for its principal object the construction of an umbrella having the functions of both a parasol and a storm umbrella.

5 The invention contemplates the provision of an umbrella provided with a double cover, the outer cover having the usual durable and water-shedding characteristics of the ordinary storm umbrella, while the inner cover 10 may be made of the more expensive and delicately colored materials usually found in parasols. The advantage of this construction is that the user of the duplex umbrella need not be deprived of the satisfaction and 15 ornamental effect attending the use of the parasol, even though the weather be inclement; nor is she subjected to the risk of spoiling a parasol, when caught in a sudden shower, since the outer cover amply protects 20 the cover beneath.

In the preferred construction the outer and inner covers are preferably spaced apart, whereby spotting of the inner cover through drawing of moisture from the outer cover 25 by capillary attraction is avoided, and this spaced relation of the covers also fulfills another object of the invention, which is to provide a heat insulating space for more effectively protecting the user of the umbrella from the heat and glare of the sun.

A still further object of the invention is to so construct a duplex umbrella that it will fold into as small a space as that usually occupied by the ordinary umbrella when 30 folded.

Other objects of the invention will appear as the description of the preferred embodiment of the invention proceeds.

In the drawings:—

40 Figure 1 is a side elevation, partly in section, through a portion of an umbrella made according to my invention, parts thereof being omitted.

45 Figure 2 is a side elevation of the frame of the umbrella showing the upper set of ribs in position to permit the replacement of the inner cover.

50 Figure 3 is a view in detail, partly in section, showing connecting means between the inner and outer sets of ribs.

Figure 4 is a section taken along the line 4—4 of Figure 3.

55 Figures 5 and 6 are respectively side and sectional views of the rib lugs to which the stays are attached.

Referring now in detail to the several fig-

ures, the numeral 1 represents the staff of the umbrella provided at spaced intervals with the thimbles 2, 3 and 4. The lowermost of these is for the attachment of the stays 5, the others being arranged for the pivotal support of the inner and outer sets of ribs. Said ribs and stays are anchored to the thimbles in the manner customarily employed in the manufacture of umbrellas. 60 The inner and outer sets of ribs, one of each set being respectively designated by the reference numerals 6 and 7, are of usual construction, but the inner ribs are preferably slightly shorter than the outer ribs. Said 65 sets of ribs are preferably joined by means of links 8 and 9, of substantially equal length, the latter being connected to suitable lugs 10 and 11 fixed to the ribs. By means 70 of the links 8 and 9 the outer set of ribs is warped in conformity to the shape of the inner set, the adjacent ribs of the inner and outer sets being maintained in parallelism throughout the opening and closing movements of the umbrella and also when 75 it is fully opened. The stays 5 are connected to the lugs 11, and thereby indirectly serve as braces for the outer as well as the inner sets of ribs.

The outer set of ribs is provided with a 80 cover 12 which is constructed and applied in the usual manner. The inner set of ribs is provided with a cover 13. To apply this cover it is necessary to disconnect the links 8 and 9 from either the inner or outer 85 set of ribs, the point of disconnection being shown in the present embodiment adjacent the inner set of ribs, the disconnection being accomplished by withdrawing the removable cotter pin 14. The outer set of ribs may 90 then be folded upwardly into a bundle 15 of small diameter and the inner cover 13 slipped over the bundle of ribs 15 and into place, said cover being provided with a central aperture 16 for this purpose. The inner cover is also provided with apertures 17 and 18, preferably faced by eyelets, which 95 register with the lugs 11 and 10, respectively, and through which the pivotal connection 100 of the links 8 and 9 with the lower set of ribs may be restored after the inner cover 105 is in place.

It will be evident to those skilled in the art that I have devised a duplex umbrella in which the inner cover is fully protected 110 from the weather by means of the outer cover, thereby making it possible to form

the inner cover of more expensive and delicate materials. The construction also provides an inert air space between the inner and outer covers and at the same time prevents spotting of the inner cover by moisture which might be drawn by capillary action through from the outer cover if the covers were in contact. The detachable links connecting the inner and outer sets of ribs provides a facile means whereby the umbrella may be re-covered when necessary and the provision of the pivotal links 8 and 9, of substantially equal length permits the closing of the umbrella into as small a space as is occupied by an ordinary umbrella when closed, due to the flattening of the parallelogram defined by the inner and outer ribs and the links 8 and 9, incident to the closing movement of the umbrella.

20 While I have herein described what I believe to be a practical embodiment of the invention it is to be understood that numerous changes in the construction and arrangement of the parts may be made without restricting the scope of the invention.

Having described my invention what I claim as new and desire to secure by Letters Patent, is:—

1. A duplex umbrella comprising a staff, inner and outer sets of ribs supported by said staff in spaced relation, separate covers carried by said sets of ribs and means con-

necting said sets of ribs at intermediate points and at points substantially peripheral, for warping the outer set of ribs in conformity to the shape of the inner set.

2. In an umbrella, a staff, inner and outer sets of ribs foldable relatively to said staff, links pivotally connected to adjacent ribs of said sets at intermediate points and at points substantially peripheral for maintaining said ribs in substantial parallelism throughout all positions of said ribs, said links forming with said ribs a parallelogram which is flattened by the folding operation of said umbrella and separate covers carried by said sets of ribs.

3. In an umbrella a staff, inner and outer sets of ribs foldable relatively to said staff and normally spaced apart when unfolded, means connecting adjacent ribs of said sets for maintaining them in substantial parallelism throughout all positions of said ribs, said means being disconnectable from the ribs of one set to permit the outer set of ribs to be folded upwardly independently of the inner set of ribs, and independent covers for said sets of ribs, the inner cover being replaceable by passing it over the upper set of ribs when the latter are upwardly folded.

In testimony whereof I have hereunto set my hand.

WILLIAM GEORGE GREY.
